MEANS FOR CONTROLLING INDUCTION ELECTRICITY METERS

Application filed January 15, 1927, Serial No. 161,327, and in Switzerland January 29, 1926.

The invention relates to induction electricity meters and more particularly to new and useful corrective or compensating devices for maintaining substantially correct 5 readings of the meter notwithstanding variations in temperatures.

Objects and advantages of the invention will be set forth in part hereinafter and in part will be obvious herefrom, or may be 10 learned by practice with the invention, the same being realized and attained by means of the instrumentalities and combinations pointed out in the appended claims.

The invention consists in the novel parts, 15 constructions, arrangements, combinations and improvements herein shown and described.

The accompanying drawing, referred to herein and constituting a part hereof, illustrates one embodiment of the invention, and together with the description, serves to explain the principles of the invention.

The drawing is a diagrammatic elevation 20 of the driving system of an induction meter embodying one form of the invention.

In practice nearly all induction meters show plus errors with increases in temperature, and vice versa, at least at unity power factor. It is usually stated that the meters 25 have a positive temperature coefficient, and this coefficient is the mean additional error per degree centigrade between two definite temperatures, as for example, between 20 degrees and 50 degrees.

These temperature errors are caused primarily, or at least in part, by the action of the 30 brake magnet, as its flux decreases with a rise in temperature, and increases when the temperature drops. The meter driving system 35 also acts, under temperature variations, in partly causing these errors.

Previous efforts and means for correcting or compensating for these errors have been directed to neutralizing the temperature 40 reactions of the brake magnet.

The present invention is directed to new and useful means for counteracting the errors, or that part of the error in the meter 45 registrations due to the influences of temperature variations on the driving system.

In most induction meters the temperature coefficient varies with changes in the power factor. That is, at a fifty per cent power factor the temperature coefficient is smaller than at unity power factor due to increase 55 in the ohmic resistance in the pressure coil.

If the temperature coefficient at unity power factor is being decreased through relative increase in the braking action due to rise in temperature, the same result is caused at 60 fifty per cent power factor, and if a total compensation is effected for such change in the braking action at unity power factor, this compensation will cause a negative error at fifty per cent power factor due to increase 65 in the resistance in the pressure coil.

The present invention has in view the neutralization of variations in the action of the driving system through variations in the resistance of the pressure coil due to temperature changes, and also the compensation of variations in the brake magnet action, thereby eliminating in a high degree the errors due to temperature changes. More in detail by 70 my invention, the changes in resistance in the pressure coil and the changes of the braking force of the brake magnet due to variations in temperature, are compensated for by effecting changes in the torque so as to retain substantially proportional the relation of the 75 torque to the brake action of the magnet under all power factor conditions.

By my invention an additional magnetic circuit is provided in the air gap of the magnetic shunt circuit, the flux thereof changing 80 proportionally to changes in temperature. Its resistance is rendered changeable by the use of a bi-metallic strip or member, the metals of which have different coefficients of expansion, whereby the air gap is increased 85 or diminished with the changes in temperature. The resultant variations in this additional magnetic circuit will thus correspondingly vary the action of the driving flux on 90 the meter discs.

By this additional regulating circuit the phase displacement, which would otherwise be affected by the change in the ohmic resistance of the pressure coil is maintained 95 substantially undisturbed. There is thus eff- 100

fected a compensation for the temperature disturbances in induction meters.

The single figure of drawing shows diagrammatically an exemplary specific embodiment of the invention, but it will be understood that various changes may be made therein as may be found desirable or efficient. In said exemplification, the driving core 1 carries a pressure coil 2 and current coils 3. The core 1 is formed with an extension 6 with an air gap 4 between the end thereof and the middle part of core 1.

The embodied means for varying the width of air gap 4 comprises a strip 5, consisting of two attached strips of metal having different co-efficients of expansion, any of the known suitable metals being used. This compound strip 5 is mounted upon the end of the part 6 of the core. The relative width of the gap at 4 and 5 will, of course, be correctly proportioned for the best and most efficient operation of the device. Any usual or suitable device for varying the phase angle may also be used in the gap 4.

At normal temperatures, the strip 5 will be preferably parallel to the core 1, as shown in the drawing, when it is inactive with reference to producing a magnetic shunt circuit. With a rise in temperature, the strip 5 will move toward the core 1, and thereby will establish a magnetic shunt circuit, across the gap to the adjacent part of core 1. Thus the driving flux is decreased, and the resultant corrective agencies are created, as already fully described, whereby the errors arising from changes in the ohmic resistance of the pressure coil and in the brake magnet action, due to variations in temperature are neutralized.

It will be understood that the structure and manner of use of a particular embodiment may be varied from the present disclosure without departing from the principles of the invention and without sacrificing its chief advantages.

What I claim is:

1. In combination in an induction electricity meter a pressure electro-magnetic coil and core having a magnetic shunt circuit with an air gap and a bimetallic strip movable by temperature variations to modify the magnetic flux at the air gap.

2. In combination a series coil and core, a pressure coil and core, said core being formed to provide a shunt circuit having an air gap, and a bimetallic member at the air gap, and movable by temperature changes to vary the magnetic flux in the shunt circuit.

3. In testimony whereof, I have signed my name to this specification.

WILLI BEUSCH.
